RAILWAY SIGNALING

George R. Pflasterer, Swissvale, Pa., assignor to
The Union Switch & Signal Company, Swiss-
vale, Pa., a corporation of Pennsylvania

Application July 18, 1936, Serial No. 91,418

13 Claims. (Cl. 246—50)

My invention relates to railway signaling, and particularly to railway signaling involving way-side signals for governing the passage of trains along a stretch of track. Specifically, my invention relates to new and novel means for supplying a current of distinctive character to the rails of each of three sections in the rear of an occupied section whereby there is produced a three-block, four-indication, system of signaling. My invention is, in part, an improvement upon that disclosed and claimed in an application for United States Letters Patent, Serial No. 26,784, filed June 15, 1935, by James J. Vanhorn, for Railway signaling.

I will describe two forms of apparatus embodying my invention, and will then point out the novel features thereof in claims.

Figs. 1A and 1B of the accompanying drawings are diagrammatic views, which when placed end to end in the order named, illustrate one form of apparatus embodying my invention. Fig. 2 is a diagrammatic view illustrating a modification of a portion of the apparatus shown in Figs. 1A and 1B, and also embodying my invention.

Similar reference characters refer to similar parts in each of the several views.

Referring first to Figs. 1A and 1B, the reference characters 1 and 2 designate the rails of a stretch of track over which traffic normally moves in the direction indicated by the arrows. The stretch is divided by insulated joints 3 into track sections W—X, X—Y, and Y—Z. Located at the entrance to each track section is a signal designated by a suitable distinguishing reference character. Each signal includes an upper indication unit U and a lower indication unit L. As here shown, each upper indication unit U is a semaphore arm capable of assuming a horizontal or "stop" position, and a 45° or "caution" position, and a vertical or "proceed" position. Each lower unit U is a semaphore arm capable of assuming a horizontal or "stop" position and a vertical or "proceed" position.

For controlling the signals, each section is provided with a polarized direct current track relay and with a neutral direct current track relay designated by the reference characters ATR and BTR, respectively, each with a prefix the same as the reference character of the associated signal. Each direct current track relay ATR is connected directly across the rails of the associated track section and each neutral track relay BTR is connected across the rails of the associated section by an asymmetric unit, a transformer, and a condenser designated by the refer-

ence characters Q, P, and J, respectively, each with a prefix the same as the reference character of the associated signal. As will be explained more in detail hereinafter, the rails of each section are at times supplied with direct current only and at other times supplied with alternating current simultaneously with direct current. The impedance of the polarized track relays ATR is of such value that the flow of alternating current in these relays will be substantially prevented. The transformers P will prevent the flow of direct current from the rails into the neutral track relays BTR and the condensers J will prevent the flow of direct current from the rails into the primary windings of the transformers P.

Each section is provided with a source of direct current here shown as a battery and designated by the reference character TB with a prefix the same as the reference character of the associated signal.

For controlling the polarity of the direct current supplied to the track circuit in the rear, each section is provided with a pole changing relay designated by the reference character PC with a prefix the same as the associated signal. As will be explained more in detail hereinafter, each PC relay is energized when the associated track relay BTR is energized or when the associated track relay ATR is energized in the normal direction provided the associated track relay BTR is then deenergized.

For supplying alternating current to the rails of the section next in rear, each section is provided with a transformer having a secondary winding 10 and a primary winding 11. Each secondary winding 10 is connected between the associated battery TB and the rails of the section next in rear.

For supplying alternating current to the primary winding 11 of the transformers N, each section is provided with a device designated by the reference character A with a prefix the same as the associated signal.

As here shown, each device A is an alternator of the vibrating reed type. Referring to alternator 7A, for example, an elastic member 12 is caused to vibrate between terminals 13 and 14 by a control winding 15. In the deenergized condition of alternator A, member 12 does not connect with either terminal 13 or 14 but does connect with a terminal 16. When energy is supplied to the alternator, winding 15 will attract member 12 causing it to connect with terminal 14 and to move away from terminal 16, causing winding 15 to become deenergized. Upon the deenergization of

winding 15, the resilience of member 16 will cause it to move away from terminal 14 and to connect with terminal 13 as well as with terminal 16. The circuit for winding 15 being then again completed through terminal 16, winding 15 will again attract member 12 causing the cycle of operation just described to be repeated. Winding 15, therefore, will be repeatedly energized and deenergized as long as energy is supplied to its control circuit. When member 16 is in engagement with contact 13, the left-hand portion of primary winding 11 of transformer 7N will be energized in one direction, whereas when member 16 is in engagement with contact 14, the right-hand portion of primary winding 11 will be energized in the reversed direction. Alternating current, therefore, will be induced in secondary winding 10 of transformer 7N as long as alternator 7A is operating.

20 The track relays ATR and BTR control the signals in the following manner: When relay ATR is deenergized (see signal 8), both semaphore arms U and L of signal 8 will be caused to assume the horizontal position to indicate "stop". When relay ATR is energized in the reverse direction (see signal 7), a caution circuit for the upper semaphore arm U of that signal is closed so that that signal is displaying its upper semaphore arm in the caution position and its lower semaphore arm 30 L in the stop position to indicate "approach next signal prepared to stop". This caution circuit may be traced from terminal B of any suitable source of energy through front contact 20 of relay 7ATR and semaphore arm U to terminal C of the same source of energy. When the relay ATR is energized in the reverse direction and the relay BTR is also energized, the caution circuit for the upper semaphore arm U remains closed and a proceed circuit for the lower semaphore arm L is closed so that signal 6 displays its upper semaphore arm U in the caution position and its lower semaphore arm L in the proceed position to indicate "approach next signal at medium speed". The proceed circuit for the lower semaphore arm L may be traced from terminal B over front contact 21 of relay 6ATR, reverse polar contact 22-23 of relay 6ATR, front contact 24 of relay 6BTR, and lower semaphore arm L to terminal C. When relay ATR is energized in the normal direction (see signal 5), the caution circuit for the upper semaphore arm U remains closed and a proceed circuit for the upper semaphore arm is closed so that signal 5 is caused to display its upper semaphore U in the proceed position and a lower semaphore arm L in the stop position to indicate "proceed at normal speed". The proceed circuit may be traced from terminal B over front contact 25 of relay 5ATR, normal polar contact 22-26 of relay 5ATR, and upper semaphore arm U to terminal C.

65 As here shown, a train K is indicated diagrammatically in the section immediately to the right of location Z so that both relays 8ATR and 8BTR are deenergized. Under this condition, the rails of section Y-Z are supplied with direct current of reverse polarity so that relay 7ATR is energized in the reverse direction. The circuit for relay 7ATR may be traced from one terminal of track battery 8TB through resistor 27, back point of contact 28 of relay 8PC, secondary winding 10 of transformer 8N, rail 1, relay 7ATR, rail 2, and back point of contact 29 of relay 8PC to the other terminal of track battery 8TB.

70 Since relay 7ATR is energized in the reverse direction and relay 7BTR is deenergized, a cir-

cuit is closed to cause the operation of alternator 7A. This circuit may be traced from terminal B over back point of contact 30 of relay 7BTR, front contact 31 of relay 7ATR, reverse polar contact 32-33 of relay 7ATR, and alternator A to terminal C.

75 Since relay 7PC is deenergized and secondary winding 10 of transformer 7N is energized by alternating current, the rails of section X-Y are supplied with direct current in the reverse direction and with alternating current so that relay 6ATR is energized in the reverse direction and relay 6BTR also is energized. The circuit for relay 6ATR may be traced from one terminal of track battery 7TB through resistor 27, back point 15 of contact 34 of relay 7PC, secondary winding 10 of transformer 7N, rail 1, relay 6ATR, rail 2, and back point of contact 35 of relay 7PC to the other terminal of track battery 7TB. The circuit for the energization of relay 6BTR may be traced 20 over the same path as just described for relay 6ATR except including condenser 6J, transformer 6P, and asymmetric unit 6Q in place of relay 6ATR.

25 Since relay 6BTR is energized, relay 6PC also 25 is energized over the front point of contact 36 of relay 6BTR so that direct current is supplied in the normal direction to the rails of section W-X to cause relay 5ATR to be energized in the normal direction. The circuit for relay 5ATR may be 30 traced from one terminal of track battery 6TB through resistor 27, front point of contact 37 of relay 6PC, rail 2, relay 5ATR, rail 1, secondary winding 10 of transformer 6N, and front point of contact 38 of relay 6PC to the other terminal of 35 track battery 6TB. Since relay 5ATR is energized in the normal direction and relay 5BTR is deenergized, the relay 5PC will be energized to supply the rails of the section immediately in the rear of location W with direct current in the normal direction so that the signal (not shown) for such rear section will be displaying the normal proceed indication. The circuit for relay 5PC may be traced from terminal B over the back point of contact 39 of relay 5BTR, front point of 45 contact 40 of relay 5ATR, normal polar contact 32-41 of relay 5ATR, and relay 5PC to terminal C.

40 The relays PC are provided with a slow-releasing characteristic in order that these relays will not release during the period when they are being transferred from control by the front point of the associated relay BTR to control by the back point of such relay BTR and the associated relay ATR. For example, when the train K vacates the section immediately to the right of 55 location Z so that relay 6BTR becomes deenergized and relay 6ATR becomes energized in the normal direction to cause signal 6 to display the normal proceed indication, the relay 6PC, even though momentarily deenergized, will not become 60 released during this period to disturb the energization of the rails for the section W-X.

50 Referring now to Fig. 2, I have shown herein one signal and associated apparatus which, when connected in a system, will provide three-block, 65 four-indication, signaling similar to that described for the apparatus shown in Figs. 1A and 1B.

70 The reference character CTR designates an alternating current polarized track relay connected by a condenser J to the rails of the section associated with the signal and the reference character DTR designates a neutral direct current relay also connected to the rails of such associated section. Associated with the relay CTR 75

is a winding 42 which is permanently connected to any convenient source of alternating current, the terminals of which are designated by the reference characters BX and CX. The impedance of the relay DTR will be of such value as to prevent the flow of alternating current in this relay and the condenser J will prevent the flow of direct current in the relay CTR.

10 For supplying direct current to the rails of the rear section, the usual track battery TB is provided, and for supplying alternating current to the rails of the rear section, a transformer M is provided having a primary winding 43 and a secondary winding 44. The primary winding 43 is connected to the terminals BX and CX of the source of alternating current and the secondary winding 44 is connected across the rails in one direction or the other in accordance with the condition of an alternating current pole changing relay designated by the reference character PCX.

The relays CTR and DTR control the semaphore arms U and L in a manner identical to that described for the relays ATR and BTR shown in Figs. 1A and 1B. Since the signal control circuits may be very readily traced, it is not considered necessary to give a detailed description of these circuits.

30 When the relays CTR and DTR are both de-energized the relay PCX will also be deenergized to supply alternating current in the reverse direction to the rails of the rear section over the back points of contacts 45 and 46 of relay PCX and back point of contact 47 of relay CTR.

When relay CTR is energized in the reverse direction and relay DTR is deenergized, direct current will be supplied to the rails of the rear section simultaneously with alternating current in the reverse direction over back points of contacts 45 and 46 of relay PCX and front point of contact 47 of relay CTR.

When either relay DTR is energized, or relay CTR is energized in the normal direction and relay DTR is deenergized, relay PCX will be energized to supply alternating current in the normal direction to the rails of the rear section over front points of contacts 45 and 46 of relay PCX. One circuit for relay PCX may be traced from terminal BX over front point of contact 48 of relay DTR and the other circuit may be traced from terminal BX over the back point of contact 48 of relay DTR, front contact 49 of relay CTR, and normal polar contact 50—51 of relay CTR.

55 The relay PCX is provided with a slow releasing characteristic so that its front points will not become open to disturb the energization of the rails of the rear section during the time this relay is being transferred from control by the front point of contact 48 of relay DTR to control by the back point of contact 48 and relay CTR.

Although I have herein shown and described only two forms of apparatus embodying my invention, it is understood that various changes and modifications may be made therein within the scope of the appended claims without departing from the spirit and scope of my invention.

Having thus described my invention, what I claim is:

70 1. A railway signal system comprising a plurality of sections of railway track, means effective when one section is occupied to supply the rails of the section next in rear of such occupied section with only direct current of one polarity, means then effective to supply the rails of the section

second in rear of such occupied section with alternating current simultaneously with direct current of said one polarity provided the section next in rear of such occupied section is unoccupied, means then effective to supply the rails of the section third in rear of such occupied section with only direct current of the other polarity provided the second section in rear of such occupied section is also unoccupied, and traffic governing means for each section selectively responsive to the character and number of currents supplied to the rails of the associated section.

2. In combination, a forward section and a rear section of railway track, a polarized track relay and a neutral track relay for the forward section, means effective when the forward section is unoccupied to energize only the polarized relay in the reverse direction or to energize the neutral relay simultaneously with the energization of the polarized relay in the reverse direction or to energize only the polarized relay in the normal direction according to traffic conditions in advance of the forward section, means effective when both the polarized and neutral relays are deenergized to supply the rails of the rear section with current of one character, means effective when the polarized relay is energized in the reverse direction and the neutral relay is deenergized to supply the rails of the rear section with current of a different character simultaneously with current of said one character, and means effective when the neutral relay is energized or when the polarized relay is energized in the normal direction provided the neutral relay is deenergized to supply the rails of the rear section with current of still a different character.

3. In combination, a forward section and a rear section of railway track, a polarized track relay and a neutral track relay for the forward section, means effective when the forward section is unoccupied to energize only the polarized relay in the reverse direction or to energize the neutral relay simultaneously with the energization of the polarized relay in the reverse direction or to energize only the polarized relay in the normal direction according to traffic conditions in advance of the forward section, a pole changing relay which is energized when the neutral relay is energized or when the associated polarized relay is energized in the normal direction provided the neutral relay is then deenergized, means for supplying the rails of the rear section with current of one character or of another character according as said pole changing relay is energized or de-energized, respectively, and means for supplying the rails of the rear section with current of a different character simultaneously with current of said other character effective when said polarized relay is energized in the reverse direction provided said neutral relay is then deenergized.

4. In combination, a forward section and a rear section of railway track, a polarized track relay and a neutral track relay for the forward section, means effective when the forward section is unoccupied to energize only the polarized relay in the reverse direction or to energize the neutral relay simultaneously with the energization of the polarized relay in the reverse direction or to energize only the polarized relay in the normal direction according to traffic conditions in advance of the forward section, a pole changing relay which is energized when the neutral relay is energized or when the associated polarized relay is energized in the normal direction provided the neutral relay is then deenergized.

- neutral relay is then deenergized, means for supplying the rails of the rear section with current of one character or another character according as said pole changing relay is energized or deenergized respectively, and means for supplying the rails of the rear section with current of a different character simultaneously with current of said other character effective when said pole changing relay is deenergized provided said polarized relay is then energized.

5 5. In combination, a forward section and a rear section of railway track, a polarized track relay and a neutral track relay for the forward section, means effective when the forward section is unoccupied to energize only the polarized relay in the reverse direction or to energize the neutral relay simultaneously with the energization of the polarized relay in the reverse direction or to energize only the polarized relay in the normal direction according to traffic conditions in advance of the forward section, a pole changing relay, a circuit for said pole changing relay including a front contact of the neutral relay, another circuit for said pole changing relay including a back contact of the neutral relay as well as a front neutral contact and a normal polar contact both of the polarized relay, and means including said pole changing relay for governing the current supplied to the rails of said rear section.

10 6. In combination, a forward section and a rear section of railway track, a polarized track relay and a neutral track relay for the forward section, means effective when the forward section is unoccupied to energize only the polarized relay in the reverse direction or to energize the neutral relay simultaneously with the energization of the polarized relay in the reverse direction or to energize only the polarized relay in the normal direction according to traffic conditions in advance of the forward section, a pole changing relay which is energized when the neutral relay is energized or when the associated polarized relay is energized in the normal direction provided the neutral relay is then deenergized, means for supplying the rails of the rear section with direct current of one polarity or of the other polarity according as said pole changing relay is energized or deenergized respectively, and means including an alternator for supplying the rails of the rear section with alternating current simultaneously with direct current of said other polarity effective when the neutral relay is deenergized provided the polarized relay is then energized in the reverse direction.

15 7. In combination, a forward section and a rear section of railway track, a polarized track relay and a neutral track relay for the forward section, means effective when the forward section is unoccupied to energize only the polarized relay in the reverse direction or to energize the neutral relay simultaneously with the energization of the polarized relay in the reverse direction or to energize only the polarized relay in the normal direction according to traffic conditions in advance of the forward section, a pole changing relay which is energized when the neutral relay is energized or when the associated polarized relay is energized in the normal direction provided the neutral relay is then deenergized, means for supplying the rails of the rear section with direct current of one polarity or of the other polarity according as said pole changing relay is energized or deenergized respectively, a transformer having a primary winding and a secondary winding, said secondary winding being connected in series with the rails of the rear section next in rear, and means for supplying said primary winding with alternating current when said polarized relay is energized in the reverse direction provided said neutral relay is then deenergized.

20 8. In combination, a forward section and a rear section of railway track, a polarized track relay and a neutral track relay for the forward section, means effective when the forward section is unoccupied to energize only the polarized relay in the reverse direction or to energize the neutral relay simultaneously with the energization of the polarized relay in the reverse direction or to energize only the polarized relay in the normal direction according to traffic conditions in advance of the forward section, a pole changing relay which is energized when the neutral relay is energized or when the associated polarized relay is energized in the normal direction provided the neutral relay is then deenergized, means for supplying the rails of the rear section with direct current of one polarity or of the other polarity according as said pole changing relay is energized or deenergized respectively, a transformer having a primary winding and a secondary winding, said secondary winding being connected in series with the rails of the section next in rear, an alternator for each section having its output terminals connected to said primary winding, and a circuit for said alternator including a back contact of the associated neutral relay as well as a front neutral contact and a reverse polar contact both of said polarized relay.

25 9. In combination, a forward and a rear section of railway track, a polarized track relay and a neutral track relay for the forward section, means effective when the forward section is unoccupied to energize only the polarized relay in the reverse direction or to energize the neutral relay simultaneously with the energization of the polarized relay in the reverse direction or to energize only the polarized relay in the normal direction according to traffic conditions in advance of the forward section, a pole changing relay for the forward section which is energized when the neutral relay is energized or when the polarized relay is energized in the normal direction provided the neutral relay is then deenergized, means effective to supply the rails of the rear section with only alternating current of reverse polarity when the pole changing relay is deenergized provided the polarized relay also is deenergized, means effective to supply the rails of the rear section with direct current simultaneously with alternating current of reverse polarity when the pole changing relay is deenergized provided the polarized relay is energized, and means effective to supply the rails of the rear section with only alternating current of normal polarity when the pole changing relay is energized.

30 10. In combination, a forward and a rear section of railway track, a polarized track relay and a neutral track relay for the forward section, means effective when the forward section is unoccupied to energize only the polarized relay in the reverse direction or to energize the neutral relay simultaneously with the energization of the polarized relay in the reverse direction or to energize only the polarized relay in the normal direction according to traffic conditions in advance of the forward section, a pole changing relay for the forward section which is energized

when the neutral relay is energized or when the polarized relay is energized in the normal direction provided the neutral relay is then de-energized, a source of direct current, a trans-
 5 former provided with a primary winding and a secondary winding, said primary winding being connected to a source of alternating current, means including a back contact of said pole changing relay and a back contact of said polar-
 10 ized relay for connecting said secondary winding across the rails of the rear section in one direc-
 15 tion, means including a back contact of said pole changing relay and a front contact of said polarized relay for connecting said source of direct current across the rails of the rear section in series with said secondary winding in said one direction, and means including a front con-
 20 tact of said pole changing relay for connecting said secondary winding across the rails in the other direction.

11. In combination, a forward and a rear sec-
 25 tion of railway track, a polarized track relay and a neutral track relay for the forward section, means effective when the forward section is un-
 30 occupied to energize only the polarized relay in the reverse direction or to energize the neutral relay simultaneously with the energization of the polarized relay in the reverse direction or to energize only the polarized relay in the normal direction according to traffic conditions in ad-
 35 vance of the forward section, a pole changing relay for the forward section which is energized when the neutral relay is energized or when the polarized relay is energized in the normal direc-
 40 tion provided the neutral relay is then deener-
 45 gized, a source of direct current, a source of alternating current, means effective to connect said source of alternating current across the rails in one direction or the other according as said pole changing relay is energized or deenergized respectively, and means effective to connect said source of direct current in series with said alternating current when said pole changing relay is deenergized provided said polarized relay is then energized.

12. A railway signal system comprising a plurality of sections of railway track, means effective when only one section is occupied to supply the rails of the section next in rear of such occupied section with only alternating current of one polarity, means then effective to supply the rails of the section second in rear of such occupied section with direct current simultaneously with alternating current of said one polarity pro-
 5 vided the section next in rear of such occupied section is unoccupied, means then effective to sup-
 10 ply the rails of the section third in rear of such occupied section with only alternating current of the other polarity provided the second section in rear of such occupied section is also unoc-
 15 cupied, and traffic governing means for each section selectively responsive to the character and number of currents supplied to the rails of the associated section.

13. In combination, a forward and a rear sec-
 20 tion of railway track, a polarized track relay and a neutral track relay for the forward section, means effective when the forward section is un-
 25 occupied to energize only the polarized relay in the reverse direction or to energize the neutral relay simultaneously with the energization of the polarized relay in the reverse direction or to energize only the polarized relay in the normal direction according to traffic conditions in ad-
 30 vance of the forward section, a pole changing relay for the forward section which is energized when the neutral relay is energized or when the polarized relay is energized in the normal direc-
 35 tion provided the neutral relay is then deener-
 40 gized, a source of direct current, means effective to connect said source of direct current across the rails of the rear section in the normal direction or the reverse direction according as said pole changing relay is energized or deenergized re-
 45 spectively, and means for also supplying alter-
 50 nating current to the rails of the rear section effective when said polarized relay is energized in the reverse direction provided said neutral relay is then deenergized.

GEORGE R. PFLASTERER. 45
